UNITED STATES PATENT OFFICE.

JONAS JONSSON, OF LEONARDVILLE, KANSAS, ASSIGNOR OF ONE-THIRD TO FRED C. MILLER AND ONE-THIRD TO JOHN A. JOHNSON, BOTH OF LEONARDVILLE, KANSAS.

COMBINED EXTENSIBLE OR ADJUSTABLE AND FOLDABLE STEPLADDER.

1,342,542.

Specification of Letters Patent.

Patented June 8, 1920.

Application filed October 8, 1919. Serial No. 329,208.

To all whom it may concern:

Be it known that I, JONAS JONSSON, a citizen of the United States, residing at Leonardville, in the county of Riley and State of Kansas, have invented certain new and useful Improvements in Combined Extensible or Adjustable and Foldable Step-ladders, of which the following is a specification, reference being had to the accompanying drawings.

This invention relates to a combined extensible or adjustable and foldable step-ladder, and an object of the invention is the provision of a device of this kind, which may be constructed of various heights and of any suitable material, and wherein the parts are foldable and extensible, whereby the device may be folded so as to form a short, either two or three-foot ladder, or the parts arranged to form a ladder of greater height, preferably twice the height of the short ladder, though not necessarily.

Another object of the invention is the provision of an extensible or foldable ladder, which when folded to be used as a three-foot ladder, may be used as an excellent scaffold for paperhangers' walking board, in other words a support for the walking board.

As a further object of the invention, it is the aim to construct a step-ladder in any length, and to provide a step-ladder which is durable in every respect, either when used as a household article or when used by decorators, paperhangers and others.

A still further object of the invention is to provide a step-ladder which is light, and which is convertible from a three-foot ladder to a six-foot ladder and when extended as a six-foot ladder means such as an automatic slide is employed including a link brace between the opposite portions of the ladder, to insure rigidity when in use.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-

after set forth, shown in the drawings and 55 claimed.

In the drawings:

Figure 1 is a view showing the ladder folded in compact form.

Fig. 2 is a perspective view showing the 60 ladder opened, and supported by two parts of the ladder.

Fig. 3 is a side view of the ladder open, whereby opposite portions of the ladder 65 may constitute two legs, and whereby a part of another portion constitutes a third leg interposed between the first two legs.

Fig. 4 is a perspective view showing the ladder extended and opened and being substantially twice the height of the ladder 70 shown in Figs. 2 and 3.

Referring more especially to the drawings, 1 designates the dominant ladder section and 2 denotes the ladder supporting section. The ladder section comprises two 75 parts 3 and 4, the part 3 constitutes the upper portion of the ladder when extended, and the part 4 constitutes the base or lower portion. These parts 3 and 4 comprise the 80 side rails 5 and 6, and connecting these side rails are the ladder steps 7 and 8. These steps are dove-tailed into the side rails as shown at 9. However, the rear parts of the 85 steps are extended beyond the side rails, and secured to the ends of the rear edges of the steps are the brace rails 10 and 11, thereby 90 reinforcing the steps, as well as reinforcing the parts of the dominant ladder section. The adjacent ends of the brace rails 10 and 11 are hingedly united as shown at 12, 90

whereby the two parts of the dominant ladder section are capable of folding upon each other, as shown clearly in the drawings. Secured between the side rails 5 of the upper section of the ladder is a step 13, which 95 constitutes one of the top steps of the ladder, when folded to form a three-foot step ladder. A brace piece 14 is secured to the upper step of the upper part of the upper section 3 of the dominant ladder section, 100 and by means of the hinges 15, the brace section of the step-ladder is hingedly connected to the brace piece. This brace section of the step-ladder comprises two parts 16 and 17 hingedly united as at 18. The 105 upper part 16 of the brace section comprises the side rails 19, which are relatively reinforced by the braces 20. An additional

brace 21 connects the two side rails 19 of the upper part of the brace section, and this additional brace 21 is beveled, as illustrated. It will be noted that the braces 20 and 21 are secured to the side rails 19 of the upper part of the brace section to the faces nearest the dominant ladder section. The lower part 17 of the brace section comprises the side rails 22, which are relatively reinforced by the braces 23 and 24. A slide 25 is provided, and which comprises a transversely disposed piece slidably engaging the rear faces of the side rails of the lower part of the brace section. A link brace 27 is hingedly connected to the sliding transverse piece 25 as at 28, and is in turn hingedly connected at 29 to the uppermost step of the lower part of the dominant ladder section, so as to reinforce the dominant ladder section and brace section relatively to each other, when the ladder is extended and the sections open. In order to guide the transversely disposed sliding piece 25, it is provided with a pair of arms 26, which are disposed in parallelism and are arranged intermediate the side rails 22 of the lower part of the brace section. These arms 26 are adapted to slide between the braces 20 and 24, and when the slide is moved upwardly to its fullest extent, the upper ends of the arms (which are beveled as shown at 30) cam against the inclined rear faces of the brace 21, and since the upper portion of the rear face of the transverse brace 21 protrudes rearwardly of the side rails, the arms of the slide are rigidly reinforced, when they are in their upper positions. Angle pieces 31 constructed of any suitable material, preferably metal, though not necessarily, are secured to the brace 24 and the side rails 22 of the lower part of the brace section, and between these angle members or plates and the brace 24 the arms 26 are guided, hence insuring proper guiding of the arms, as well as additionally reinforcing the slide, and also reinforcing the upper and lower parts of the brace section, particularly at their hinged connections, when the upper and lower parts of the brace section are opened or extended.

Secured to the link brace is an abutment 32, which is engaged by the transverse brace 24, when the lower part of the brace section is collapsed against the lower part of the dominant ladder section, thereby holding the lower part of the brace section in engagement with the lower part of the dominant ladder section. To further assist in holding these parts together when the ladder is opened and used as a stool step-ladder, a turn button 33 is disposed in engagement with one of the rails of the lower part of the brace section. It will be noted that 60 when the dominant ladder and brace sections

are collapsed against each other, the hinges connecting the upper and lower parts of both sections are axially alined, so that the upper and lower parts of the two sections may fold toward each other. When the 70 parts of the two sections are folded substantially in parallelism to each other, the ladder is in compact form, and when in such condition may be placed in storage for safe keeping. When so folded a hook 34 linked to 75 one of the side rails of the upper part of the dominant ladder section detachably engages an eye 35 on one of the side rails of the lower part of the ladder section, thereby holding the two parts together. However, 80 when the upper part of the dominant ladder section is extended to form a ladder of considerable height, this hook engages an eye 36, thereby holding the upper and lower parts rigid. An elongated loop 37 is linked to 85 one of the side rails 10 of the dominant ladder section. A wire guide loop 39 is secured to the edge of one of the brace rails 11 of the lower part of the dominant ladder section, with which the loop 90 37 engages. This wire guide loop is curved as shown and the curved part constitutes a cam, and is provided with a drop or offset portion 40, with which the end of the loop 39 engages, when the upper and lower parts 95 of both sections of the ladder are partially folded so that the device may be used as a stool ladder, thereby reinforcing the upper and lower parts of the ladder. It will be noted that the interengaging loops of the 100 two parts of the dominant ladder and brace sections do not interfere with the extensibility of the upper part of the dominant ladder section, when it is desired to extend the device to form a ladder of considerable 105 height. When the parts of the two sections of the ladder are arranged to form a short ladder, such as shown in Fig. 3, the lower part of the brace section of the ladder may be disposed intermediate the upper and 110 lower parts of the ladder sections, thereby providing a three-foot ladder. In this case, the device may be used as an excellent scaffold for a wall or ceiling decorator or used as a scaffold for a paper-hangers' walking 115 board. In order to dispose the lower part of the brace section, to form the third leg of the ladder, the brace 24 is disengaged from the abutment, in which case the lower part of the brace section may be disposed intermediate the two parts of the ladder sections.

Secured on the rear face of the side rails 22 of the lower part of the brace section are stops or abutments 41, which are engaged by the transverse slide 25, to limit the slide in 125 its upward movement, when the dominant ladder and brace sections are separated and when the device is used as a six-foot ladder. The slide and its link which connects between the opposite portions of the ladder to 130

insure strength and rigidity, may be used in connection with any length of ladder.

The invention having been set forth, what is claimed as new and useful is:

- 5 1. In a foldable and extensible ladder, the combination with dominant ladder and brace sections hingedly united, each of said sections comprising hingedly united upper and lower parts, the hinged connections between 70
10 said parts being axially alined when the brace section is collapsed against the dominant ladder section, whereby the upper and lower parts of both sections may be hingedly separated to form a short ladder, a link brace 75
15 connected to one of the parts of the dominant ladder section and having a sliding connection with the lower part of the brace section, to hold the brace section inclined in a bracing position from the dominant ladder 80
20 section, when the ladder is extended and opened, said link brace having means to engage a member of the brace section, to hold the lower part of the brace section collapsed against the lower part of the dominant ladder 85
25 section, when the ladder is used as a stool ladder.
2. In a ladder, the combination with dominant ladder and brace sections hingedly united, whereby one may be opened and inclined at an acute angle from the other section, a link brace hingedly connected to the dominant ladder section, a slide carried by 90
30 the brace section to which the link brace is connected for reinforcing the two sections, the brace section comprising upper and lower hinged parts, said slide having means 95
35 slidably coöperatively engaging between portions of the two parts of the brace section and positioned across the hinged connections of the two parts to reinforce the parts of the brace section when the ladder is 100
40 extended.
3. In a ladder, the combination with dominant ladder and brace sections hingedly united, whereby one may be opened and inclined at an acute angle from the other section, a link brace hingedly connected to the dominant ladder section, a slide carried by 105
45 the brace section to which the link brace is connected for reinforcing the two sections, the brace section comprising upper and lower hinged parts, said slide having means 110
50 slidably coöperatively engaging between portions of the two parts of the brace section and positioned across the hinged connections of the two parts to reinforce the parts of the brace section when the ladder is 115
55 extended, and means carried by one of 120
60 the parts of the brace section to limit the movement of said slide.
4. In a ladder, the combination with dominant ladder and brace sections hingedly united, whereby the two sections may be inclined from each other and capable of col- 125
65 lapsing toward each other, a link brace carried by the dominant ladder section and having a slidable connection with the brace section, the dominant ladder and brace sections comprising upper and lower parts, hingedly united substantially midway the height of the extensible ladder, said hinged connections being correspondingly located midway the height of the ladder, whereby the hinges are axially arranged when the brace section is collapsed against the dominant ladder 130

section, whereby the parts of both sections may fold toward each other, to form a short ladder, means carried by the upper and lower parts of the dominant ladder section 5 for bracing the upper and lower parts of both sections, when said upper and lower parts are partially folded, after having disposed the brace section adjacent the dominant ladder section, the lower part of the brace section being adapted to be disposed between the upper part of the brace section 10 and the lower part of the dominant ladder section, whereby the device may be used as

a three-foot ladder, and an abutment carried by the link brace to engage a member 15 of the lower part of the brace section, to assist in holding the lower part of the brace section collapsed against the lower part of the dominant ladder section, when the device is used as a short step-ladder, and means 20 to further assist in holding the lower part of the brace section in contact with the lower part of the dominant ladder section.

In testimony whereof I hereunto affix my signature.

JONAS JONSSON.
